MEANS FOR DECORATING SCREEN WIRE

Richard Burdick, Dallas, Tex.

Application May 14, 1949, Serial No. 93,265

5 Claims. (Cl. 154—1.6)

1

This invention relates in general to certain new and useful improvements in means for decorating screen wire and is related to my copending application Serial No. 93,266, filed May 14, 1949.

For advertising purposes, it has been found desirable and expedient to emboss, imprint, or otherwise form a plaque-like advertising display upon a defined area of a piece of woven screen wire which is inserted in a conventional manner in the door screens and window screens of commercial establishments. Because of the fact that every customer entering and leaving the establishment will see a sign or other advertising display which is incorporated in the screen door, such advertising media are particularly useful, but, by the same token, are subjected to extreme conditions of wear and tear. Frequent slamming of the door tends to jar the advertising display loose, the display is frequently brushed against as the door is opened and closed, and, of course, it is continuously exposed to the weather and, since screen doors are normally used in the summertime, the advertising sign or display is ordinarily exposed to the heat of the sun for a number of hours each day and, therefore, tends to dry out and become extremely brittle.

Heretofore, advertising screen wire has been manufactured by the so-called silk screen process. This method is substantially a hand process, since each piece of screen wire must be placed in a suitable jig or holding fixture beneath the silk screen and a proper screening compound squeegeed through the silk into the interstices of the screen wire. In order to achieve an attractive eye-catching result through the employment of several different colors, it obviously becomes necessary to employ several different screens through which the different colors of screening compounds may be passed and it is necessary to permit each piece of screen wire to dry before the next successive application of screening compound. Obviously, such procedure must be carried out to very close register and is time-consuming.

It is, therefore, the primary object of the present invention to provide means and methods for embellishing screen wire with a plaque-like advertising element which is extremely rugged, durable, and attractive in appearance and can be introduced into or applied upon the screen wire automatically and with a minimum of hand labor.

It is a further object of the present invention 55 flights in such manner that, when the flights

2

to provide automatic means for embellishing screen wire by the application thereto of a plaque-like advertising element.

It is an additional object of the present invention to provide means and methods of the type stated which are simple, economical, and capable of substantially continuous operation.

With the above and other objects in view, my invention resides in the novel features of form, construction, arrangement and combination of parts presently described and pointed out in the claims.

In the accompanying drawings (two sheets)—

Figure 1 is a top plan view of a screen wire 15 decorating machine constructed in accordance with and embodying the present invention;

Figure 2 is a longitudinal sectional view taken along line 2—2 of Figure 1;

Figure 3 is a fragmentary side elevational view 20 of the screen wire decorating machine showing in more detail the gear drive to the heated rollers thereof;

Figure 4 is a fragmentary sectional view taken along line 4—4 of Figure 1;

Figures 5 and 6 are fragmentary sectional views taken along lines 5—5 and 6—6, respectively, of Figure 2;

Figure 7 is a fragmentary sectional view taken along line 7—7 of Figure 6;

Figure 8 is a fragmentary sectional view taken along line 8—8 of Figure 5;

Figure 9 is a fragmentary sectional view taken along line 9—9 of Figure 5;

Figure 10 is a fragmentary sectional view taken along line 10—10 of Figure 2;

Figure 11 is a fragmentary perspective view of a section of screen wire embellished with a plaque-like advertising element; and

Figure 12 is a fragmentary sectional view taken along line 12—12 of Figure 11.

Broadly speaking, the present invention comprises a horizontal table having upper and lower conveyor runs extending thereacross. The upper and lower conveyors are provided with flights and are driven in timed relation, so that, as the conveyors move across the table, one of the flights of the upper run will always be superimposed in vertical alignment with one of the flights of the lower run. Means is also provided for continuously feeding a web of screen wire between the conveyor runs and provision is made for feeding into the flights sections of thermo-plastic material having a selected or predetermined peripheral contour and being positioned within the flights

are superimposed, the two sections of thermo-plastic or fusible material will be in peripheral registration on opposite sides of the web of screen wire and moving along with it. In such position, the sections are passed between a plurality of pairs of heated rolls which serve to soften the sections of thermo-plastic or fusible material and force them through the interstices of the screen wire and merge with each other. Thereafter, the screen wire may be passed between additional rolls, if necessary, to smooth or, if desired, emboss the oppositely presented faces of the now completely merged and consolidated plastic plaque-like advertising element. Finally, the web of screen wire thus embellished may, if desired, pass beneath a suitable cut-off mechanism for severance into sections of suitable length.

Referring now more specifically and by reference characters to the drawings, which illustrate a preferred embodiment of the present invention, A designates a screen wire decorating machine comprising a horizontally disposed framework 1 formed of side rails 2, 3, transversely welded at their ends to cross rails 4, 5, and supported above the floor upon legs 6. Welded or otherwise secured to and extending horizontally between the legs 6 in downwardly presented relation to the frame 1 is a reinforcing sub-frame 7 similarly including cross rails 8, 9, and longitudinally extending side rails 10. Rigidly mounted upon and extending horizontally between the side rails 10, approximately midway of the length of the machine A, is a shelf plate 11 for supporting a conventional electric motor 12 which is drivingly connected to a conventional gear reduction box 13 having a power output shaft 14, which is, in turn, conventionally provided with a driving sprocket 15. The electric motor 12 is connected to a conventional switch 16 to any suitable source of electric current (not shown).

Welded along its longitudinal margins to and extending horizontally between the side rails 2, 3, is a relatively heavy gauge sheet metal table plate 17 which is substantially coincident at its forward end (reference being had to the right side of Figures 1 and 2) with the end rail 5, and at its opposite or rearward end the table plate 17 terminates in inwardly spaced relation to the end rail 4 and is marginally bent downwardly in the provision of a curved lip 18. Approximately midway of its length the table 17 is provided with three transversely spaced parallel slots 19 separated by relatively narrow bridging bars 20 and directly forwardly thereof the plate 17 is further provided with a transversely extending somewhat wider slot 21 separated from the adjacent slot 19 by a wide bridging bar 22. Forwardly of the slot 21 is a transversely extending wide slot or opening 23, the forward transverse margin of which is bent downwardly in the provision of a curved lip 24.

Welded to and extending vertically upwardly from the side rails 2, 3, in alignment with the opening 23 are posts 25, 26, respectively, and similarly welded to the side rails 2, 3, and extending vertically upwardly therefrom in rearwardly spaced parallel relation to the posts 25, 26, are posts 27, 28, having rearwardly projecting horizontal trunnion bars 29, 30. Journaled at their ends in and extending horizontally between the posts 25, 26, in upwardly spaced relation to the table plate 17 are shafts 31, 32, provided with pairs of sprockets 33, 34. At their lower ends, the posts 25, 26, project downwardly a short distance below the side rails 2, 3, and journaled in

and extending horizontally between such downwardly projecting ends is a shaft 35, also provided with sprockets 36. One of the sprockets 33 is aligned with one of the sprockets 34, which is, in turn, vertically aligned with one of the sprockets 36 in such a manner that the three sprockets 33, 34, and 36 on one side of the machine lie in substantially the same vertical plane while the corresponding sprockets 33, 34, 36, on the opposite side of the machine also lie in the same vertical plane. Similarly, journaled in and extending horizontally between the posts 27, 28, are shafts 37, 38, located in horizontal alignment, respectively, with the shafts 31, 32, and are provided with pairs of sprockets 39, 40. One of the sprockets 40 is vertically aligned on one side of the machine with one of the sprockets 39 and these two sprockets are also horizontally aligned with the sprockets 33, 34, 36, and similarly the other sprocket 40 is vertically aligned with the other corresponding sprocket 39 on the opposite side of the machine and these latter two sprockets are likewise horizontally aligned with the sprockets 33, 34, 36, on that side of the machine.

Welded to and projecting a short distance downwardly from the side rails 2, 3, are bracket plates 41 located along a transverse line which lies approximately midway between the end rail 4 and the curved lip 18 of the table plate 17. Journaled in and extending horizontally between the bracket plates 41 beneath the table plate 17 is a shaft 42 located in horizontal alignment with the shaft 35 and provided with sprockets 43 which are horizontally aligned with the sprockets 36. On one of its ends, the shaft 35 projects outwardly beyond the side rail 2 and is provided with driving sprockets 44, 45, the latter being connected by a conventional roller chain 46 to the main driving sprocket 15. Inwardly of the side rail 2, the shaft 35 is further provided with a spur gear 47, which is of somewhat larger diameter than the sprockets 36 and projects along the upper portion of its periphery through the opening 23 in the table plate 17 for meshing engagement with a similar spur gear 48 pinned to the shaft 31.

Trained around each horizontally aligned set of sprockets 36, 43, are conveyor chains 49 for carrying a uniformly spaced series of horizontal flight plates 50. The size of the sprockets 36, 43, and the location of the shafts 35, 42, is such that the upper horizontal run of the conveyor chains 49 will extend slidingly across the upwardly presented face of the table plate 17 and the flight plates 50 are so mounted on the chains 49 that they will ride horizontally forwardly over the table plate 17 with their under faces in slightly upwardly spaced relation to the upwardly presented face of the table plate 17. Similarly trained around each set of sprockets 33, 34, 39, 40, is a conveyor chain 51 likewise provided at uniformly spaced intervals with transversely extending flight plates 52. The sprockets 33, 34, 39, 40, are so positioned that the lower horizontal run of the conveyor chains 51 will extend across the table plate 17 in upwardly spaced relation to the corresponding horizontal run of the conveyor chains 50, and the flight plates 52 are so positioned that they will each be located in precise vertical alignment for coincident travel with a corresponding flight plate 50. The flight plates 52, 50, are furthermore provided centrally of their forward leading edges as they travel together forwardly across

the table plate 17 with vertically aligned semi-circular recesses 53, 54, respectively. It will be noted by reference to Figure 5 that the flight plates 50, 52, are so arranged that they are spaced vertically apart from each other during the course of their travel together forwardly over the table plate 17 whereby to accommodate therebetween a traveling web of screen wire *w* which is fed downwardly around a suitably mounted idler roll 55 from a supply roll 56, which is conventionally trunnioned in the trunnion bars 29, 30. It will be noted in this connection that the idler roll 55 is located just rearwardly of the sprockets 39 and substantially forwardly of the sprockets 43. Thus the flight plates 50 will travel for a substantial distance over the table plate 17 before they pass under, and begin to take up travel with, the screen wire web *w*, for purposes presently more fully appearing.

Rigidly secured to the side rails 2, 3, are roller mounting plates 57, 58, positioned in and extending along that portion of the frame 1 in which the slots 19, 21, are located. Journaled in and extending horizontally between the roller mounting plates 57, 58, is a plurality of pairs of hollow heated rollers 59, 60, each such pair of rollers 59, 60, being vertically aligned on opposite sides of one of the openings 19 and being spaced from each other by a distance somewhat greater than the combined thickness of the screen wire web *w* and a vertically aligned matching pair of flight plates 50, 52. At one end, the hollow rollers 59, 60, are respectively provided with axially extending stub shafts 61, 62, which are journaled in and extend through the plate 58 and at their outer ends are provided with intermeshing spur gears 63, 64. At their opposite ends, the rollers 59, 60, are provided with axially extending tubular shafts 65, 66, communicating at their inner ends to the interior of the rollers and at their opposite ends being journaled in and extending through the plate 57 for rotative disposition within manifolding collars 67, 68, which are, in turn, connected to steam headers 69, 70, all as best seen in Figure 5.

Journaled in and extending horizontally between the mounting plates 57, 58, forwardly of the rollers 19 and vertically aligned on opposite sides of the gap 21 are large smoothing rolls 71, 72. The shafts of the rolls 71, 72, project outwardly through the plate 58 and are provided with intermeshing spur gears 73, 74. Rotatably mounted upon the external face of the plate 58 and meshingly interposed between each of the spur gears 63 and between the forwardmost gear 63 and the spur gear 73 are small idler gears 75, so that all of the several gears 63, 64, 73, 74, will be intermeshed and the rollers 59, 60, 71, 72, will move simultaneously and at the same peripheral speed. The shaft of the roller 72 furthermore projects outwardly beyond the spur gear 74 and is provided with a sprocket 76 which is drivingly connected by means of a roller chain 77 to a sprocket 78 keyed upon the outwardly projecting end of the shaft 35. Similarly journaled in and extending horizontally between the rails 2, 3, forwardly of the shafts 31, 35, and adjacent to the lip 24 is a pair of vertically aligned stripping rollers 79 to facilitate separation of the flight plates 50, 52, from the screen wire web *w*.

Welded to and extending vertically upwardly from the side rails 2, 3, forwardly of the lip 24 are transversely aligned bracket plates 80 having vertical slots 81 for receiving vertically shift-

able upper and lower journal blocks 82, 83, normally biased toward each other by compression springs 84, 85, respectively. Journaled in and extending horizontally between the journal blocks 82, 82, and 83, 83, are horizontal shafts 86, 87, respectively, and pinned thereto are suitably spaced pairs of driving wheels 88, 89, respectively, formed preferably, though not necessarily, of rubber and being vertically aligned through apertures 90, 91, suitably located in the table plate 17. Thus, when the screen wire web *w* is fed between the pairs of rubber driving wheels 88, 89, the latter will be forced toward each other by the springs 84, 85, so as to securely engage the screen wire web *w* without deforming it. The shaft 86 extends outwardly beyond the side rail 2 and on such extended end is provided with a sprocket 92 which is drivingly connected by means of a roller chain 93 to the sprocket 44.

Rigidly mounted upon and extending vertically upwardly from the side rails 2, 3, forwardly of the bracket plates 80, are transversely aligned posts 94 cross-connected at their upper ends by a stabilizing beam 95. Rigidly mounted upon and extending vertically above and below the beam 95 is a conventional hydraulic cylinder 96 having a downwardly extending shiftable piston rod 97 connected at its lower end centrally of a vertically disposed shearing blade 98, which is, in turn, provided at its opposite ends with integrally formed outwardly extending ears 99 slidably disposed between way-forming bars 100 bolted or otherwise rigidly secured to the inwardly presented faces of the posts 94. Directly beneath the shearing blade 98, the table plate 17 is provided with a transversely extending clearance slot 101 having a rearward edge 102 ground off for shearing co-operation with the sharpened edge of the shearing blade 98. The hydraulic cylinder 96 is connected by means of oil tubes 103 to a conventional hydraulic pump and control valve (not shown), the latter being arranged to actuate the hydraulic cylinder at predetermined or timed intervals in relation to the speed of movement of the screen wire web *w* for severing the latter into sections of desired length. If desired, a mechanical shear driving mechanism of any conventional design may be substituted for the hydraulic cylinder 96.

In operation, steam of an appropriate temperature is admitted through the tubular shafts 65, 66, to the rollers 59, 60. If desired, hot oil or electric heating elements may be employed instead of steam. When the rollers 59, 60, have reached the desired temperature, the switch 16 is turned, energizing the motor 12, which, acting through the gear reduction box 13, the sprocket 15, and the roller chain 46, drives the shaft 35 and with it the shafts 31, 32, 37, 38, 42, and the roller chains 49, 51, causing the flight plates 50, 52, to move around into paired position over the table plate 17 and thence forwardly between the rolls 59, 60, and 71, 72. Rotation of the shaft 35 is transmitted through the roller chain 77 and the sprocket 76 to the spur gears 73, 74, and thence to the spur gears 63, 64, so that the rollers 59, 60, 71, 72, all begin to rotate. Similarly, the rotation of the shaft 35 is transmitted through the roller chain 93 and the sprocket 92 to the shaft 86 and the driving wheels 88 are thereby turned, propelling the screen wire web *w* forwardly.

As each flight plate 50 comes up onto the upper horizontal run and moves over the lip 18 onto the table plate 17, it is in the clear for a short interval of time before it travels beneath the idler

roller 55 and passes under the traveling screen wire web *w*. During this interval, the operator may manually place in the recess 53 a plaque 104 of relatively thin thermo-plastic sheet material which has been preformed by die-cutting or any other suitable process. Similarly, as the flight plates 52 move downwardly and around into the forwardly traveling horizontal run above the moving screen wire web *w*, each such flight plate 52 will be in the clear, so to speak, during the interval that it traverses the distance between the shaft 37 and the first pair of heated rollers 59, 60. Thus, the operator will manually place a second preformed thermo-plastic element or plaque 105 in the recess 54, which is thereupon carried forwardly on top of the screen wire web *w* in marginally registered alignment with the plaque 104, which is sliding along the upper surface of the table plate 17 on the under side of the screen wire web *w*. Held in this relation by the flight plates 50, 52, the screen wire web and the superposed plaques 104, 105, pass between the successive pairs of heated rollers 59, 60, and are thereby softened and pressed together, so that they will, in effect, flow through the interstices of the screen wire web *w* and fuse with each other to form a solid background element B. Upon continuation of forward travel, the screen wire web *w* and the fused background element B pass between the smoothing rolls 71, 72, which are set at such a distance as to lightly engage the oppositely presented faces of the background element B and impart thereto a relatively smooth, even surface or finish. Thereafter, the screen wire web *w* with its smoothed background element B pass between the stripping rollers 79, which insure complete separation of the flight plates 50, 52. Finally, the screen wire web *w* passes beneath the shearing blade 98, which is actuated as previously described, to sever the screen wire web *w* into sections of desired length.

The outwardly presented faces of the background element B may thereafter be painted, imprinted, embossed, or decorated in any other conventional manner for artistic or advertising purposes as may be required.

It should be understood that changes and modifications in the form, construction, arrangement, and combination of the several parts of the screen wire decorating machine and in the several steps of the screen wire decorating methods may be made and substituted for those herein shown and described without departing from the nature and principle of my invention.

Having thus described my invention, what I claim and desire to secure by Letters Patent is:

1. A screen wire decorating machine comprising a flat surfaced table-like element, means for rotatably supporting a roll of screen wire over said table-like element, means for feeding a continuous web of screen wire from said roll onto and across said table-like element from a line spaced inwardly from one end of said table-like element so as to leave an uncovered intake apron on the table-like element ahead of the screen wire, a first flight conveyor mounted operatively upon the table-like element and having flights positioned for movement initially across the intake apron and thence beneath the web of screen wire, said flights being contoured in their leading edges for receiving a plaque of thermoplastic material and pushing the plaque across the surface of the table-like element therebeneath the web of screen wire for movement therewith, a second flight conveyor operatively mounted on the opposite side

of the web of screen wire with respect to the first flight conveyor and having a plurality of flights positioned for movement above and with the web of screen wire, said last named flights being also contoured in their leading edges for receiving a plaque of thermoplastic material and holding it upon the upper surface of the web of screen wire, said flight conveyors being timed for movement at the same rate of speed as the web of screen wire and furthermore so that a flight of each conveyor will be coincident and travel together with the web of screen wire thereby causing the thermoplastic plaques respectively carried by each to move in superposed marginal registration with each other and on opposite faces of the screen wire, and heated rollers disposed on opposite sides of the web of screen wire for riding over the outwardly presented faces of said plaques and simultaneously heating them and pressing them toward each other so as to fuse them together to each other through the interstices of the screen wire.

2. A screen wire decorating machine comprising a flat surfaced table-like element, means for rotatably supporting a roll of screen wire over said table-like element, means for feeding a continuous web of screen wire from said roll onto and across said table-like element from a line spaced inwardly from one end of said table-like element so as to leave an uncovered intake apron on the table-like element ahead of the screen wire, a first flight conveyor mounted operatively upon the table-like element and having flights positioned for movement initially across the intake apron and thence beneath the web of screen wire, said flights being contoured in their leading edges for receiving a plaque of thermoplastic material and pushing the plaque across the surface of the table-like element therebeneath the web of screen wire for movement therewith, a second flight conveyor operatively mounted on the opposite side of the web of screen wire with respect to the first flight conveyor and having a plurality of flights positioned for movement above and with the web of screen wire, said last named flights being also contoured in their leading edges for receiving a plaque of thermoplastic material and holding it upon the upper surface of the web of screen wire, said flight conveyors being timed for movement at the same rate of speed as the web of screen wire and furthermore so that a flight of each conveyor will be coincident and travel together with the web of screen wire thereby causing the thermoplastic plaques respectively carried by each to move in superposed marginal registration with each other and on opposite faces of the screen wire, heated rollers disposed on opposite sides of the web of screen wire for riding over the outwardly presented faces of said plaques and simultaneously heating them and pressing them toward each other so as to fuse them together to each other through the interstices of the screen wire.

3. A screen wire decorating machine comprising a flat surfaced table-like element having a transverse gap intermediate its ends, means for rotatably supporting a roll of screen wire over said table-like element, means for feeding a continuous web of screen wire from said roll onto and across said table-like element from a line spaced inwardly from one end of said table-like element so as to leave an uncovered intake apron on the table-like element ahead of the screen

wire, a first flight conveyor mounted operatively upon the table-like element and having flights positioned for movement initially across the intake apron and thence beneath the web of screen wire, said flights being contoured in their leading edges for receiving a plaque of thermoplastic material and pushing the plaque across the surface of the table-like element therebeneath the web of screen wire for movement therewith, a second flight conveyor operatively mounted on the opposite side of the web of screen wire with respect to the first flight conveyor and having a plurality of flights positioned for movement above and with the web of screen wire, said last named flights being also contoured in their leading edges for receiving a plaque of thermoplastic material and holding it upon the upper surface of the web of screen wire, said flight conveyors being timed for movement at the same rate of speed as the web of screen wire and furthermore so that a flight of each conveyor will be coincident and travel together with the web of screen wire thereby causing the thermoplastic plaques respectively carried by each to move in superposed marginal registration with each other and on opposite sides of the screen wire, and heated rollers operatively mounted in said gap above and below the surface of the table-like element and thereby being disposed on opposite sides of the web of screen wire for riding over the outwardly presented faces of said plaques and simultaneously heating them and pressing them toward each other so as to fuse them together to each other through the interstices of the screen wire.

4. A screen wire decorating machine comprising a flat surfaced table-like element, means for rotatably supporting a roll of screen wire over said table-like element, means for feeding a continuous web of screen wire from said roll onto and across said table-like element from a line spaced inwardly from one end of said table-like element so as to leave an uncovered intake apron on the table-like element ahead of the screen wire, a first flight conveyor mounted operatively upon the table-like element and having flights positioned for movement initially across the intake apron and thence beneath the web of screen wire, said flights being contoured in their leading edges for receiving a plaque of thermoplastic material and pushing the plaque across the surface of the table-like element therebeneath the web of screen wire for movement therewith, a second flight conveyor operatively mounted on the opposite side of the web of screen wire with respect to the first flight conveyor and having a plurality of flights positioned for movement above and with the web of screen wire, said last named flights being also contoured in their leading edges for receiving a plaque of thermoplastic material and holding it upon the upper surface of the web of screen wire, said flight conveyors being timed for movement at the same rate of speed as the web of screen wire and furthermore so that a flight of each conveyor will be coincident and travel together with the web of screen wire thereby causing the thermoplastic plaques respectively carried by each to move in superposed marginal registration with each other and on opposite sides of the screen wire, and heated rollers disposed on opposite sides of the web of screen wire for riding over the outwardly presented faces of said plaques and simultaneously heating them and pressing them toward each other so as to fuse them together to each other through the interstices of the screen wire.

on opposite faces of the screen wire, heated rollers disposed on opposite sides of the web of screen wire for riding over the outwardly presented faces of said plaques and simultaneously heating them and pressing them toward each other so as to fuse them together to each other through the interstices of the screen wire, and smoothing rollers disposed on opposite sides of the web of screen wire and on the opposite side of the heated rollers with respect to the intake apron for riding upon the outwardly presented surfaces of the fused plaques for smoothing said surfaces and rendering them substantially parallel to each other so that the plaques, when fused together, will form a single unit of substantially uniform thickness with smooth surfaces on opposite sides of the screen wire.

5. A screen wire decorating machine comprising means for feeding a continuous web of screen wire along a defined path so arranged that for a substantial portion of its travel along the path the screen wire travels in a flat plane, a first flight conveyor mounted operatively upon one side of the web of screen wire, said flight conveyor being provided with a plurality of spaced flights, each of which is contoured in its leading edge for receiving a plaque of thermoplastic material and feeding the plaque against the surface of the web of screen wire for movement therewith, a second flight conveyor operatively mounted on the opposite side of the web of screen wire with respect to the first flight conveyor and having a plurality of spaced flights positioned for movement with the web of screen wire, said last named flights being also contoured in their leading edges for receiving a plaque of thermoplastic material and holding it against the web of screen wire for movement therewith, said flight conveyors being timed for movement at the same rate of speed as the web of screen wire and being arranged so that the flights of one conveyor will each be respectively coincident with a corresponding flight of the other conveyor so that the pairs of coincident flights will travel together with the web of screen wire, thereby causing the thermoplastic plaques respectively carried by each to move in superposed marginal registration with each other and on opposite faces of the screen wire, and heated rollers disposed on opposite sides of the web of screen wire for riding over the outwardly presented faces of said plaques and simultaneously heating them and pressing them toward each other so as to fuse them together to each other through the interstices of the screen wire.

RICHARD BURDICK.
